[57] ABSTRACT

A fuel system, particularly for a diesel engine, has an electronic governor receiving signals from transducers associated with the engine, and providing an input to a power amplifier which determines the pump output. In order to provide a safety feature, the magnitude of the input signal applied to the power amplifier is limited to a fixed level independent of the supply voltage of the system.

FUEL SYSTEMS FOR ENGINES

This invention relates to fuel systems for engines.

A fuel system in accordance with the invention comprises in combination a pump for supplying fuel to the engine, a control member for determining the output of the pump, an actuator for varying the setting of said control member, a power amplifier for supplying current to said actuator, a control circuit which receives at least two input signals representing the actual and demanded values of an engine parameter and provides an input to the power amplifier, and means acting to limit the magnitude of said input signal applied to the power amplifier to a fixed level independent of the supply voltage of the system.

Preferably, the control circuit includes a summing amplifier to which the signals representing actual and demanded values are fed. In this case, said means preferably includes a device for controlling the feedback in said summing amplifier.

Preferably, the system includes an overriding control which, in the event that said means fails to limit the magnitude of the input signal to the power amplifier, operates to prevent operation of the power amplifier.

In the accompanying drawings,

FIG. 1 is a circuit diagram, partly in block form, illustrating one form of fuel system with which the invention can be used,

FIGS. 2 to 4 are graphs illustrating the outputs of three transducers used in FIG. 1,

FIG. 5 represents a fuel-speed characteristic for an engine to be controlled by the arrangement of FIG. 1,

FIG. 6 is a view similar to FIG. 1 of a second form of fuel system,

FIG. 7 is a view similar to FIG. 5 but showing the characteristic obtained by FIG. 6,

FIG. 8 is a circuit diagram illustrating one example of the invention as applied to the arrangement of FIG. 1 or FIG. 6, and

FIG. 9 is a circuit diagram illustrating a modification of FIG. 8.

The examples described relate to a fuel injection system for a diesel engine driving a road vehicle, so that demand is set by an accelerator pedal. However, the arrangements shown can be used with other engines, and the engine employed need not drive a road vehicle, in which case the demand is of course set in some other way.

Referring first to FIG. 1, a fuel pump 11 supplies fuel to the cylinders of an engine 12 in turn, the fuel pump being driven in a conventional manner, with the timing of injection controlled in the usual way. The driving of the fuel pump forms no part of the present invention and is not therefore described. Moreover, the type of pump used is not critical, but in the example shown the pump is a conventional in-line pump having a control rod 14 the axial position of which determines the rate of supply of fuel to the engine 12 by the pump 11. The axial position of the control rod 14 is controlled by an electro-mechanical actuator 13 to determine the pump output.

The system further includes three transducers 15, 16 and 17. The transducer 15 produces an output in the form of a voltage shown in FIG. 2, the magnitude of the voltage being dependent on the rotational speed of the engine. The transducer 16 produces an output voltage shown in FIG. 3 the voltage being dependent on the

rate of supply of fuel to the engine, (i.e. the pump output). For this purpose the transducer 16 conveniently senses the axial position of the control rod 14 as indicated by the dotted line. The transducer 17 produces a voltage representing demand. Typically, the transducer 17 is controlled by the accelerator pedal of the vehicle which is driven by the engine, and in the particular example being described, the engine is controlled by an all-speed governor, so that the output from the transducer 17 is a voltage representing demanded engine speed. The form of this voltage is shown in FIG. 4, and it should be noted that the slope of this output is opposite to the slopes of the outputs from the transducers 15, 16.

The outputs from the transducers 15, 16 and 17 are all applied, by way of resistors 15a, 16a, 17a converting the signals to current signals, to the inverting terminal of an operational amplifier 18 connected as a summing amplifier, whilst the output from the transducer 16 is also connected through a resistor 16b to the inverting terminal of an operational amplifier 19 connected as a summing amplifier. The amplifiers 18 and 19 are powered by positive and negative supply lines 21, 22 and have their non-inverting terminals connected to a line 23 which is kept at a reference potential mid-way between the potentials of the lines 21, 22. The origin in FIGS. 2 to 4 is the potential of the terminal 23, and the supply lines are all derived from the vehicle battery.

The output from the amplifier 18 is fed through a diode 24 to a drive circuit 25 which incorporates a power amplifier and which serves to control the electro-mechanical actuator 13. Similarly, the output terminal of the amplifier 19 is connected to the drive circuit 25 through a diode 26. The diodes 24 and 26 together constitute a discriminator, which ensures that only the amplifier 18, 19 producing the more positive output is coupled to the drive circuit 25 at any given instant. Thus, if the amplifier 18 is producing the more positive output, then the diode 26 is reverse biased, and if the amplifier 19 is producing the more positive output, the diode 24 is reverse biased. FIG. 1 also shows the feedback resistors 27, 28 associated with the amplifiers 18, 19 respectively, and it will be noted that the feedback circuit for each amplifier is taken from the input terminal of the drive circuit 25. By virtue of this arrangement, the effective forward voltage drop across the diodes 24 and 26 is reduced by a factor dependent upon the amplifier open-loop gain, and so the temperature characteristics of the diodes become negligible when considering the temperature characteristics of the system. Also, there is a very sharp changeover from control by one amplifier to control by the other amplifier.

The basic operation is as follows. The amplifier 18 receives current inputs representing demanded speed, actual speed and pump output.

These inputs, which are of the form seen in FIGS. 2 to 4, are compared, and if the sum of the inputs is not zero, then the amplifier 18 produces an output which is fed to the drive circuit 25, and causes the pump output to change until the sum of the inputs is zero, at which point the output from the amplifier 18 becomes such that the drive circuit 25 produces just sufficient current to keep the control rod 14 in the position it has assumed.

The amplifier 19 receives a signal by way of the resistor 16b representing pump output and also receives a

reference current from a reference source 20. If the pump output demanded by the amplifier 18 exceeds a predetermined value, then the output of the amplifier 19 will be more positive than the output of the amplifier 18, so that the diode 24 ceases to conduct as previously explained, and the amplifier 19 produces an output to the drive circuit 25. It should be noted that an increasing positive output from an amplifier 18 or 19 represents a demand for a decreasing pump output, that is to say there is an inverting stage between the amplifier and pump. When the amplifier 19 is producing an output, the system operates in the same way as when the amplifier 18 is producing an output to reduce the output of the amplifier 19 to a value such that the output from the drive circuit 25 keeps the control rod 14 in the position it has assumed. The system will stay in this condition until the amplifier 18 demands less fuel than the maximum set by the amplifier 19. When the amplifier 18 demands less fuel, it produces a greater positive output than the amplifier 19, and so takes over the operation.

Referring now to FIG. 5, the way in which the governor is designed and operates can be seen from the graph of pump output against speed. This graph also shows the effect of a number of controls not yet mentioned in relation to FIG. 1. The line 40 is set by the amplifier 18 by virtue of the way in which the comparison of actual and demanded speeds is modified in accordance with the input from the transducer 16. The line 40 in the drawings represents 50 percent demand, and is one of a family of lines stretching from 0 percent demand to 100 percent demand. The extremes of this family, that is to say no demand and full demand, are indicated at 38 and 43. The line 38 is set by a current source 31 providing an input to the inverting terminal of the amplifier 18, to ensure that the engine speed varies with pump output in the manner indicated by the line 38 even when the demand is zero. The maximum speed is set by a control 29 shown in FIG. 1 and which acts by limiting the maximum demand from the transducer 17. The line 35 is the maximum fuel line which is set by the amplifier 19 as previously explained.

The boundary line 39 is a function of the engine, not the governor, and represents the no-load fuel requirements of the engine under different demands, so that the points 41 and 42 are the no-load engine speeds at zero and full demand, (i.e. with the pedal released and fully depressed respectively).

FIG. 5 explains how the engine will behave in any circumstances. Suppose that the pedal has been set to demand 50 percent, corresponding to the line 40 shown in FIG. 5. The exact position on the line 40 at any given instant will depend upon the load on the engine, and so for this given setting of the pedal, the engine speed can vary within the limits set by the lines 35 and 40. The slope of the line 40 is, as previously explained, a result of the input to the amplifier 18 from the transducer 16. Assuming that the engine is operating at a particular point on the line 40, then if the vehicle starts to go up an incline, the load will increase, and so for a given position of the pedal the operating point will move up the line 40, so that the speed is reduced. If the load becomes sufficiently great, the line 35 will be reached, and no further increase in pump output will be permitted. At this point, the speed falls rapidly. If the load decreases, then the operating point moves down the line

40 with the corresponding increase in speed. If the load decreases to zero, the line 39 is reached.

If the demand is changed, then assuming for the sake of argument that it changes from 50 percent demand to 100 percent demand, the pump output will increase as rapidly as the pump and governor will allow until the line 35 is reached, and the engine will then move along the line 35 onto the maximum demand line 43, and will assume a position on the line 43 which is dependent upon the load.

If the demand is reduced, then assuming the demand is reduced from 50 to 0 percent, the operating point will move downwards until the fuel supply is zero. The speed then decreases until the line 38 is reached, after which the operating point moves up the line 38, finishing at a point on the line 38 determined by the load on the engine.

Turning now to FIG. 6, there is shown a second example in which the governor is a two-speed governor, that is to say a governor in which the demand signal is a fuel signal which is compared with the actual fuel, the pump output then being modified to provide the desired fuel output. In FIG. 6, the amplifier 18 receives a signal from the transducer 16 by way of the resistor 16a, this signal representing actual fuel. A signal representing demanded fuel is fed by way of the resistor 17a to the amplifier 18, but it will be noted that there is no speed term fed to the amplifier 18 from the transducer 15. The characteristics of the system are shown in FIG. 7. The line 40a is one of a family of horizontally extending lines which are set by the governor, and can be taken to represent the 50 percent demand line. When the pedal sets a demand of 50 percent, the amplifier 18 sets the required fuel level. The operating point on the line 40a will of course then depend on the load on the engine.

The amplifier 19 overrides the amplifier 18 in FIG. 6 in a similar manner to the arrangement in FIG. 1, except that the amplifier 19 now receives a signal by way of the resistor 15a representing speed, and also a reference current from a source 20a indicating the maximum engine speed. The amplifier 19 sets the maximum speed of the engine, which is indicated by the line 43 in FIG. 7. It will be noted that the line 43 has a slope, that is to say the maximum permitted speed varies with pump output. This slope is obtained by feeding to the amplifier 19 a signal representing pump output, this signal being fed by way of the resistor 16b.

The maximum pump output, that is to say the line 35 in FIG. 7, is set by a control 29a which limits the maximum demand, in much the same way as the control 29 limits the maximum speed in FIG. 1. The minimum engine speed, indicated by the line 38, is set by a current source 31a, which is similar to the current source 31 except that because the current source 31a acts on the amplifier 18, which does not receive a speed term, the current source 31a must receive a speed term as indicated by its connection to the transducer 15.

Referring now to FIG. 8, the lines 23, 22 are interconnected through a diode 51 and a resistor 52 in series, and the junction of the diode 51 and resistor 52 is connected through a pair of resistors 53, 54 respectively to the bases of a pair of n-p-n transistors 55, 56. The transistors 55, 56 have their emitters connected through diodes 57, 58 respectively to the output terminals of the amplifiers 18, 19 and their collectors connected to the inverting input terminals of the amplifiers

18, 19 respectively. Moreover, the junction of the diode 51 and resistor 52 is also connected through a resistor 61 to the base of an n-p-n transistor 62 the emitter of which is connected through diodes 63, 64 in series to the output terminal of the amplifier 18 and through the diode 63 and a diode 65 in series to the output terminal of the amplifier 19. The collector of the transistor 62 is connected to a safety network 66 coupled to the amplifier 25, and the cathode of the diode 26 is connected to the line 22 through a resistor 70.

The arrangement shown in FIG. 8 can be used in conjunction with the arrangement of FIG. 1 or with the arrangement of FIG. 6. The purpose of the transistors 55 and 56 is to minimise the risk of damage to components within the power amplifier 25 in the event that the power amplifier 25 receives a dangerously high input signal from one of the amplifiers 18, 19. A high input signal to the amplifier 25 can arise, by way of example, whenever the demand is increased suddenly.

Considering first the amplifier 18, the base potential of the transistor 55 is fixed and is negative with respect to the line 23. Thus, in order for the transistor 55 to conduct, its emitter potential must be even more negative with respect to the line 23 than its base. If the demand is increased rapidly, then the amplifier 18 will produce a large negative output signal with respect to the line 23. This large negative signal at the output terminal of the amplifier 18 will permit current to flow through the resistor 53 to turn the transistor 55 on. The transistor 55 now provides a low resistance feedback path between the output terminal of the amplifier 18 and its inverting input terminal, and this feedback path acts to limit the negative increase in the input signal provided to the amplifier 25. Thus, the input signal to the power amplifier is limited to a fixed level independent of the battery voltage.

The transistor 56 acts in exactly the same way in relation to the amplifier 19.

The purpose of the transistor 62 and its associated components is to effect a control if the output of either amplifier 18, 19 becomes so negative with respect to the terminal 22 that the transistors 55, 56 cannot cope with the situation. The diode 63 is included so that as the potential at the output terminal of one of the amplifiers 18, 19 becomes increasingly negative, the transistors 55 and 56 turn on before the transistor 62. However, when the transistor 62 does turn on, it provides an input signal to the safety network 66 which operates the amplifier 25 to prevent damage to the amplifier 25. The network 66 can, for example, turn the amplifier 25 off.

Referring now to FIG. 9, the arrangement is similar to FIG. 8, and the same references have been used. An additional diode 51a is included in series with the diode 51, and the transistors 55, 56 have their base resistors 53, 54 and emitter diodes 57, 58 omitted, and their emitter and collector connections to their respective amplifiers 18 and 19 reversed as compared with FIG. 8. In this example, the inputs to the amplifiers 18, 19 are sensed, but these inputs will of course be equal to the outputs, and so the operation is not altered. The transistor 62 operates as in FIG. 8, but the diode 63 is not needed.

We claim:

1. A fuel injection system for a compression-ignition engine, comprising in combination a pump for supply-

ing fuel to the engine, an electro-mechanical actuator coupled to the pump to determine the pump output, a drive circuit for controlling the electro-mechanical actuator, first, second and third transducers producing respectively output voltages representing engine speed, pump output and demanded pump output, a first operational amplifier connected as a summing amplifier and having its inverting input connected through resistors to the second and third transducers, said first amplifier producing an output representing the difference between the actual and demanded pump outputs and also serving to restrict the maximum pump output to a predetermined value, a second operational amplifier connected as a summing amplifier and having its inverting input connected through resistors to the first and second transducers, a discriminator coupling the outputs of the amplifiers to the drive circuit, the arrangement being such that until a predetermined engine speed is attained, the discriminator couples the first amplifier to the drive circuit, but when said predetermined engine speed is reached, the discriminator couples the second amplifier to the drive circuit to limit the maximum engine speed, the maximum engine speed being varied with pump output by the second amplifier, a first low resistance feedback circuit connected between the output terminal and the inverting input of the first operational amplifier, a switching device in said feedback circuit, means for turning said switching device on when the output of the first amplifier reaches a predetermined level, a second low resistance feedback circuit connected between the output terminal and the inverting input of the second operational amplifier, a second switching device in said second feedback circuit, and means for turning the second switching device on when the output of the second amplifier reaches a predetermined value.

2. A fuel injection system for a compression-ignition engine, comprising in combination a pump for supplying fuel to the engine, an electro-mechanical actuator coupled to the pump to determine the pump output, a drive circuit for controlling the electro-mechanical actuator, first, second and third transducers producing respectively output voltages representing engine speed, pump output and demanded engine speed, a first operational amplifier connected as a summing amplifier and having its inverting input connected through resistors to the first, second and third transducers, said first amplifier producing an output representing the difference between the actual and demanded engine speed, but the difference being modified in accordance with the input received from the second transducer so as to provide the required engine characteristics, a second operational amplifier connected as a summing amplifier and having its inverting input connected through a resistor to the second transducer, a discriminator coupling the outputs of the amplifiers to the drive circuit, the arrangement being such that until a predetermined pump output is attained, the discriminator couples the first amplifier to the drive circuit, but when said predetermined rate of supply of fuel is reached, the discriminator couples the second amplifier to the drive circuit to limit the maximum rate of supply of fuel, a first low resistance feedback circuit connected between the output terminal and the inverting input of the first operational amplifier, a switching device in said feedback circuit, means for turning said switching device on when the output of the first amplifier reaches a predeter-

mined level, a second low resistance feedback circuit connected between the output terminal and the inverting input of the second operational amplifier, a second switching device in said second feedback circuit, and

means for turning the second switching device on when the output of the second amplifier reaches a predetermined value.
